UNITED STATES PATENT OFFICE

FRANK E. GRUNWALDT, OF SEATTLE, WASHINGTON

FORCED-DRAFT FAN

Application filed June 14, 1927. Serial No. 198,734.

The invention is a fan adaptable to be installed in connection with the inlet air duct of hot air heating furnaces which operates in the duct and does not decrease the area of the duct to any appreciable amount.

5 The object of the invention is to provide a fan for a forced draft in a furnace inlet duct which operates in the duct and at the same time does not decrease the area to any appreciable amount.

10 Another object of the invention is to provide a fan for a forced draft duct which operates in one side of the duct and at the same time increases the velocity of the air in the entire duct.

15 Another object of the invention is to provide means for forcing air through a duct in which a baffle is used in combination with a fan to increase or decrease the area adjacent to the fan to vary the pressure or velocity.

20 A further object of the invention is to provide a forced draft fan which may operate in a duct without decreasing the area which may be installed so that all noise and vibration may be eliminated.

25 And a still further object of the invention is to provide a fan for a forced draft air duct which will operate in the duct without decreasing the area to any appreciable amount, which is of a simple and economical construction.

30 With these ends in view the invention embodies a rotary fan having curved blades, means for installing the fan in one side of an air duct, means for rotating the blades, a suitable housing covering part of the blades with a seal in it and a baffle plate to cooperate with the said fan.

35 Other features and advantages of the invention will appear from the following description taken in connection with the drawings, wherein:

40 Figure 1 is a side view of a bend in a duct showing the device in place.

45 Figure 2 is a cross section through the duct looking toward the fan.

Figure 3 is a longitudinal section through the fan.

50 Figure 4 is a cross section through the fan and fan housing.

Figure 5 is a detail showing a connection between the end of a duct and a furnace housing to show that the duct is insulated against vibration and noise by a deadening washer at all connections.

55 Figure 6 is a view showing an alternate arrangement in which the fan is located in the side of a straight duct.

60 In the drawings the device is shown as it would be made wherein numeral 1 indicates the fan, numeral 2 the fan housing, and numeral 3 the duct.

65 The fan is constructed as shown in Figures 3 and 4 with a cylinder 5 having closed ends formed with solid hubs 6 and 7 flanged at their outer edges and at their centers and mounted on a shaft 8 and it will be seen that the interior of the cylinder is sealed. The shaft 8 is mounted in bearings 9 and 10 which are supported in posts 11 and 12. In the design shown the posts are illustrated as being made of wood with diagonal braces 13 at the bottom to hold them in an upright position. However, it is understood that these posts may be of any suitable material or any suitable frame may be used. The motor 14 is mounted on the foundation and will drive the shaft 8 through a belt 15 and pulleys 16 and 17.

70 The cylinder 5 is provided with a plurality of blades 18 which are made as shown in Figure 4 and attached to the cylinder by bolts or rivets, as shown. The fan is mounted in one side of the duct and provided with a housing 2, which covers the part 75 of the fan that is outside of the duct and the housing may be divided with a joint 19 so that a portion of it may be removed if desired. One side of the housing is held in a joint 20, which is known as a Pittsburg lock, 80 in the top of the horizontal duct and the other side is held in a joint 21 in the side of the vertical section of the duct. The edges of the housing 2 are formed as shown in Figure 3 so that they will have recesses 85 22 and flaps 23 which may be bent downward over the upper edge of the side members, which are indicated by the numeral 24. It will be observed that by bending the flaps 23 upward the flanges 25 at the upper edges 90 95 100

of the side members 24 may be sprung out of the recesses 22 and the housing 2 may be readily removed so that the fan may be removed through the opening in the housing. 5 A piece of felt, as indicated by the numeral 26, may also be held in the joint 20 and positioned so that it will be engaged by the edges of two of the blades 18 at one time to form a seal as the blades leave the duct, 10 which is very essential to the efficiency of the fan.

The duct 3 may be of any suitable shape, size or design and the fan may be positioned in it in any suitable manner. The fan may 15 also be held in any other suitable type of frame and the frame may be attached to the duct or built integral therewith as may be desired. In the design shown the frame is attached to the sides of the duct by angle 20 bars 27 which may be attached to the posts 11 and 12 and to the sides of the duct with a strip of deadening felt 28 between the angle bar and the duct.

In the design shown in Figure 1 a baffle 25 plate 29 is hinged in the duct at the point 30 and provided with a lever 31 which extends outward beyond the side of the duct and to which a rod or cord 32 may be attached to adjust the position of the baffle 29. It will 30 be observed that with the baffle in the position shown in full lines the area of the duct will not be decreased, and when it is raised to the position shown in dotted lines the area 35 will be decreased and practically all of the air passing through the duct will be forced through the fan, thereby making it possible to raise the pressure of the air considerably. It is understood that a similar baffle may be used in combination with the fan shown in 40 Figure 6 and also that the baffle may be omitted, as shown in Figure 6.

In Figure 5 the duct 3 is attached to a furnace housing which is indicated by the numeral 33 by a clip 34 with an asbestos lining 45 35 for deadening the noise and eliminating the vibration.

It will be understood that changes may be made in the construction without departing from the spirit of the invention. One of 50 which changes may be in the design of the fan, as it is understood that the central part may be made in any suitable manner and the shape of the blades may also be varied considerably and the proportionate sizes of the 55 central part and blades may be varied as desired. It is also understood that any suitable number of blades may be used and any other suitable means may be used for rotating the fan. Other changes may be in the design 60 or size or arrangement of the duct, and still another may be in the use of other means for varying the area of the duct.

The construction will be readily understood from the foregoing description. To 65 use the device, the fan may be constructed

and installed as shown and described and it will be observed that as the fan is rotated in a counter-clockwise direction the blades will dip the air and force it ahead at a considerably greater velocity and if the baffle 29 is raised the pressure may be appreciably increased. It will also be observed that by adjusting the position of the fan in the duct it will be possible to increase the velocity and pressure without appreciably decreasing the 70 area of the duct, which will provide a very desirable arrangement for forced air ducts of 75 this type.

Having thus fully described the invention what I claim as new and desire to secure by 80 Letters Patent is:

1. In a device of the class described, a plurality of blades, means for mounting the said blades on a sealed rotor, said rotor being positioned with the blades extending partially into a duct or the like, and means for covering the portion of the blades extending outside of the said duct, the means for covering the outer ends of the said blades having a seal therein and a joint whereby the seal may be readily removed, and the whole being 90 readily removable.

2. In a device of the class described, a plurality of blades, means for mounting the said blades on a sealed rotor, said rotor being positioned with the blades extending partially into a duct or the like, leaving a free passage between the ends of the blades and side of the duct, means for covering the portion of the blades extending outside of the said duct, the means for covering the outer ends of the said blades having a seal therein and a joint whereby the seal may be readily removed, and the whole being readily removable, and an adjustable baffle plate for closing the opening between the ends of the blades and the opposite side of the duct. 100

3. In a device of the class described, a plurality of blades, means for mounting the said blades on a sealed rotor, said rotor being 110 positioned with the blades extending partially into a duct or the like, leaving a free passage between the ends of the blades and side of the duct, means for covering the portion of the blades extending outside of the 115 said duct, the means for covering the outer ends of the said blades having a seal therein and a joint whereby the seal may be readily removed and the whole being readily removable, and an adjustable baffle plate for closing the opening between the ends of the blades and the opposite side of the duct, said rotor, blades and baffle plate being positioned to permit an unobstructed area corresponding 120 to the area of the duct when the fan is not 125 in use.

In testimony whereof I affix my signature.
FRANK E. GRUNWALDT.
